UNITED STATES PATENT OFFICE.

ALEXANDER JAY WURTS, OF PITTSBURG, PENNSYLVANIA, ASSIGNOR TO
GEORGE WESTINGHOUSE, OF PITTSBURG, PENNSYLVANIA.

HEATER CUT-OUT FOR ELECTRIC LAMPS.

SPECIFICATION forming part of Letters Patent No. 728,647, dated May 19, 1903.

Application filed July 7, 1900. Serial No. 22,829. (No model.)

To all whom it may concern:

Be it known that I, ALEXANDER JAY WURTS, a citizen of the United States, residing at Pittsburgh, in the county of Allegheny and State of Pennsylvania, have invented a new and useful Improvement in Heater Cut-Outs for Electric Lamps, of which the following is a specification.

My invention relates to electromagnetically-actuated means for breaking electric circuits, and has particular reference to such devices as are employed for breaking the heater-circuits of electric lamps, the light-giving elements of which are conductors only when heated.

One of the objects of my invention is to provide cut-out devices for the heaters of alternating-current lamps of the character above indicated which shall obviate the humming sound ordinarily caused by alternating currents.

A further object of my invention is to provide a simple and inexpensive form of cut-out which shall have a single point of contact, or a single point for each pole in case the cut-out is of the double-pole variety, and which shall be especially adapted for use in the high temperatures to which such devices are subjected.

With these ends in view I have devised the means shown in the accompanying drawings, in which—

Figure 1 is a view, partially in section, partially in elevation, and partially diagrammatic, of a lamp having a single-pole cut-out constructed in accordance with my invention. Fig. 2 is a view similar to Fig. 1, but omitting some of the parts and illustrating a slight modification. Figs. 3 and 4 are plan views of certain details of the cut-out device. Fig. 5 is a view similar to Fig. 1, but showing a double-pole cut-out. Fig. 5^a is a side elevation of some of the parts of a modified form of a double-pole cut-out. Fig. 6 is a plan view of some of the parts shown in Fig. 5. Fig. 6^a is a detail perspective view of one of the parts shown in Fig. 5^a. Fig. 7 is a sectional view of a solenoid and core provided with an attachment for drawing one end of the core against one side of the solenoid when the former is elevated. Fig. 8 is a view of certain parts of a cut-out of modified construction,

and Figs. 9 and 10 are plan views of two of the parts shown in Fig. 8.

Electric lamps the light-giving elements of which are formed of materials that are conductors only when heated as heretofore generally constructed have embodied electric heaters located in proximity to the light-giving bodies or glowers and so arranged and connected as to be traversed by current until the glower became heated to a conducting temperature. In some cases means have been provided for withdrawing the heater from the immediate vicinity of the glower, with or without interrupting its circuit, as soon as the glower became conductive, and in other cases the heater was immovable; but means were provided for automatically interrupting its circuit as soon as the glower became conductive. Various devices have also been proposed for breaking the heater-circuit and for withdrawing the heater from the vicinity of the glower; but the means most generally employed has been a solenoid acting upon a core, the latter being connected to the movable member of the cut-out or to the heater, according as the heater-circuit was interrupted or the heater itself was moved bodily away from the glower. The operation of such devices has been in the main satisfactory, except that difficulty has been experienced on account of the humming noise caused by the vibrations of the solenoid-core when acted upon by alternating currents. It has been attempted to obviate this humming noise by providing the core of the solenoid with a cushioning-sheath; but even this by itself failed to entirely overcome the difficulty on account of the high temperatures to which the devices were subjected. It has also been proposed in some cases to employ a spring of some sort for actuating the movable member of the cut-out in the one direction or the other or to make the movable member itself of spring metal; but this practice has also been found to be unsatisfactory by reason of the high temperatures to which these parts are subjected in the lamps in which they are employed.

One of the most satisfactory forms of cut-out heretofore employed has embodied carbon contact-pieces; but these were necessarily of comparatively large dimensions on account

of the relatively poor conductivity of the material and by reason of the liability of the parts to get out of accurate adjustment.

I obviate all of the difficulties above enumerated by the means shown in the accompanying drawings, to which reference may now be had, attention being first directed particularly to Figs. 1, 2, 3, and 4. In these figures the glower 1 is formed of a material 5 that is a conductor only when heated, the current being supplied thereto from a suitable source (not shown) through conductors 2 and 3. The heater 4 for the glower may be of any desired construction, and it is also 10 supplied with current for the purpose of raising the temperature of the glower from conductors 2 and 3 through a branch conductor 5 and the contact members of the cut-out 6. The terminal of the glower that is connected 15 to the conductor 2 has a ballast device 7 and a solenoid 8 included in circuit between it and said conductor. The core 9 of the solenoid is preferably provided with a cushioning-sheath 10, of asbestos, and with a non-magnetic extension 9^a, that rests upon a thin strip 20 or ribbon 11 of flexible but inelastic metal—such, for example, as aluminium—when the solenoid is not energized. The non-magnetic extension is provided in order that the rattling noise, which might result if the ribbon 11 25 were drawn up into engagement with the bottom of the solenoid, may be avoided. One end of this strip or ribbon 11 is preferably considerably thinner than its other portions in order 30 that the upward movement of the solenoid-core when the solenoid is energized may serve to bend the strip only at that end. The said end is fastened to a terminal block 12, mounted upon a supporting-plate 13, of non-conducting material, and its other end is provided 35 with a contact-piece 14 in the form of a wire, preferably of silver or platinum, this wire being shown as extending transversely to the length of the ribbon 11 and having its ends 40 bent around the edges of the ribbon and against its top, so as to clamp the wire firmly in position. The contact-piece 14 makes contact with a wire 15, that extends at right angles with wire 14 and has its ends bent and 45 clamped around the top of a terminal block 16, supported upon the plate 13. The core extension 9^a is loosely connected to the ribbon 11 by means of a pin or screw 17, that projects through a relatively large opening 50 in the ribbon and the head of which is at a distance from the end of the core considerably greater than the thickness of the ribbon. This provides a lost-motion connection, so that the separation of the contacts 55 14 and 15 will take place when the magnetic pull upon the core is the greatest, whereby a quick break will be insured. When the core is drawn upward by the solenoid, it is mechanically held against the side of the solenoid with sufficient force to prevent vibration, 60 whereby the objectionable humming sound that has heretofore obtained in devices

employed for the same purpose is obviated. In Fig. 2 the several parts are the same as the corresponding parts shown in Fig. 1, except that the non-magnetic extension 9^a of the solenoid-core is rigidly fastened to the ribbon 11. Inasmuch as the one end of the ribbon 11 is immovably attached to the block 12 and the maximum degree of flexibility is 70 adjacent to said block, the upward movement of the core when the solenoid is energized will draw its upper end into engagement with the solenoid, as indicated in the drawings. In the construction shown in these figures 75 the ribbon 11 is extremely flexible adjacent to the block 12, as above stated, but has no spring action, the weight of the solenoid-core being sufficient to depress the ribbon and effect the closing of the circuit when the solenoid is deenergized and to maintain the circuit closed until the core is again raised by the action of the coil.

Referring now to Figs. 5 and 6, the glower 1, the heater 4, and their circuits are or may 80 be the same as those shown in the figures already described, except in so far as modifications are made to adapt the apparatus to a double-pole cut-out, and hence the description already given may be read in connection 85 with these figures so far as the same may be applicable. In these figures the non-conducting plate 13 supports two terminal blocks 12 and 12^a, that respectively have fastened to them strips or ribbons 11 and 11^a, these 90 strips being respectively provided with contact-terminals 14 and 14^a, which respectively engage with the contact-terminals 15 and 15^a, respectively mounted on blocks 16 and 16^a, the construction and operation of these parts 100 being substantially the same as the corresponding parts already described. The connection between the solenoid-core 9^c and the ribbons 11 and 11^a is made by means of a non-magnetic extension 9^b, a block or plate 105 18 of non-conducting material, to which the extension 9^b may be and preferably is rigidly attached, and wires 19 and 19^a, mounted in said block or plate and respectively bent to form loops through which the ribbons 11 and 11^a project. This arrangement affords a loose 110 connection between the solenoid-core and the ribbons, so that when the former is drawn upward by magnetic action the ribbons will 115 serve to hold it in contact with one side of the solenoid, and thus prevent vibration.

In Figs. 5^a and 6^a the parts differ from what is shown in Figs. 5 and 6 in that a small silver or platinum block or plate 20 is set into each of the terminal blocks 16^b and 16^c in lieu 125 of clamping wires to the tops of said posts. In the construction shown in these figures the wires 19 and 19^a for making connection between the ribbons and the extension 9^b of the solenoid-core 9^c are also dispensed with, 130 the block 18^a being provided with lugs 21 and 21^a on its lower side, respectively adjacent to its lateral edges, these lugs being provided with openings 22 and 22^a, through which the

ribbons 11 and 11^a respectively project. This block 18^a may be formed of porcelain or other suitable non-conducting material, and its construction is such that when the core is drawn upward the ribbons will rest against its lower side substantially throughout its width, they being thus securely held against vibration, and all noise incident to such vibration being thus avoided.

10 In each of the modifications above described the solenoid-core is supported in unstable equilibrium, and hence when raised by the solenoid it will tend to incline to one side, so as to rest against the inner wall of 15 the solenoid. When in this position, the devices shown in Figs. 5, 5^a, and 6 as embracing the strips 11 and 11^a will obviously grip the said strips closely, and consequently there will be little, if any, tendency for the parts 20 to vibrate.

In case any special means other than that already described is desired or needed for drawing the solenoid-core into engagement with the solenoid and holding it in such position against vibration any one of a considerable variety of devices may be utilized. 25 One form of such device I have shown in Fig. 7, this being a strip of metal 23, fastened to the top of the solenoid at one end and 30 having its other end projecting downward at an angle to the axis of the solenoid, so that a pin 24, projecting upward from the top of the solenoid-core, will be guided in such manner as to deflect the upper end of the core 35 and force it into engagement with one side of the solenoid. As I have already indicated, it is obvious that any one of a considerable variety of devices may be employed to effect the desired result.

40 Referring now to Figs. 8, 9, and 10, which show a single-pole cut-out device, the terminal block 16^b is shown as provided with a contact piece 20, set into a socket which may be a saw-cut of such width as to firmly hold 45 the contact-piece therein, this construction being the same as that illustrated in Fig. 5^a. The movable member of the cut-out in this form of the device comprises a thin flexible ribbon similar to that of the preceding figures; but in this case this ribbon 11^b is reinforced for the greater portion of its length on both sides by means of strips 25 of relatively inflexible material—such, for example, as phosphor-bronze—the ribbon being preferably clamped between said strips by means 55 of one or more rivets. The portion of the ribbon 11^b that projects beyond the ends of the stiffening-strips constitutes a flexible inelastic hinge, and therefore serves the same 60 function in that respect as the ribbons heretofore described. The ribbon in this instance is fastened to the terminal block 12^b by forcing its free end into a recess 26, cut in the outer face of the block, this being a 65 secure and at the same time inexpensive and ready means for attaching the ribbon to the block.

I have also shown another and very simple means for attaching the non-magnetic core extension 9^d to the ribbon 11^b and the reinforcing-plates 25. This comprises a slot 27 cut in one edge of the ribbon and the reinforcing-plates, into which a reduced portion of the extension 9^d is inserted and in which said portion fits closely, so as to make a rigid connection. This affords a secure means of attachment and also one which permits of ready assembling and detaching of the parts when desired.

Other modifications may of course be made 80 without departing from the spirit and scope of my invention, and I therefore desire it to be understood that the invention is not limited to the specific details set forth.

I claim as my invention—

1. In a heater cut-out for electric lamps, the combination with a solenoid and its core, of stationary terminals and a flexible and substantially non-resilient metal ribbon attached at different points to the solenoid-core and to 90 one terminal and having a contact-piece which is held in engagement with the other stationary terminal by gravity when the solenoid is deenergized.

2. A heater cut-out for electric lamps, comprising a solenoid, a core therefor, two stationary terminals, a flexible and substantially non-resilient metal ribbon rigidly attached at one end to one stationary terminal, and to the solenoid-core at a point between its ends, and 100 having a contact-piece that is held in engagement with the other contact-terminal by gravity when the solenoid is deenergized.

3. A heater cut-out for electric lamps, comprising two stationary terminals, a flexible 105 and substantially non-resilient movable member rigidly fastened to one of said terminals, a solenoid, and a core provided with a cushioning-sheath and attached to said movable member in such position as to hold it in engagement with the other terminal when the solenoid is deenergized.

4. In a heater cut-out for electric lamps, a movable member comprising a flexible and substantially non-resilient metal ribbon having a contact-wire clamped to one end thereof and stationary contact-terminals to one of which said ribbon is attached and with the other of which the contact-wire is held in engagement by gravity.

5. A heater cut-out for electric lamps having two terminal blocks, a solenoid and a solenoid-core, a flexible and substantially non-resilient metal strip having one end rigidly fastened to one of the terminal blocks, and 125 provided with reinforcing-strips and with a contact-piece at its free end, the other terminal block having a contact-piece seated therein with which the contact-piece on the reinforced strip is held in engagement by gravity 130 when the solenoid is deenergized.

6. In a heater cut-out for electric lamps, a movable member comprising a flexible and substantially non-resilient metal ribbon rein-

forced for a portion of its length by comparatively inflexible strips, stationary contact-terminals to one of which said ribbon is attached and with the other of which said ribbon is normally held in engagement by gravity.

5 7. In a heater cut-out for electric lamps, a movable member comprising a reinforced, metal strip or ribbon having a slot in one side or edge, in combination with a solenoid and core, said core having an extension removably seated in said slot.

10 8. In a heater cut-out for electric lamps, the combination with two stationary terminals, each of which has a slot or groove therein, of a movable member comprising a flexible, metal strip reinforced by one or more comparatively inflexible strips for a portion of its length and provided at one end with a contact-wire clamped thereon and having its 20 other end bent and seated in the slot or groove in the corresponding terminal.

15 9. An electric cut-out comprising a flexible and substantially non-resilient member movable to and normally held in circuit-closing position by gravity and electromagnetic means serving, when energized, to lift said member and hold it in open-circuit position.

20 10. In an electric cut-out, the combination with a solenoid, of a core therefor having a 30 non-magnetic extension, a flexible and substantially non-resilient ribbon to which said extension is attached and stationary terminals to one of which said ribbon is attached and upon the other of which it rests under

the action of gravity when the solenoid is de- 35 energized.

11. In a heater cut-out for electric lamps, the combination with two stationary terminal blocks one of which has a contact-piece, of a flexible and substantially non-resilient 40 metal ribbon having a contact-piece at one end to engage said terminal-block contact-piece and having its other end fastened to the other terminal block, a solenoid and a core therefor having a non-magnetic extension to 45 which the ribbon is attached at a point between its ends.

12. In a cut-out, a solenoid and its core and means for holding the core in a non-vibratory position when the solenoid is energized. 50

13. In a cut-out for alternating-current circuits, the combination with a solenoid and a cushioned core therefor, of means for mechanically holding the core against the inner wall of the solenoid when the solenoid is energized. 55

14. A heater cut-out for electric lamps of the type described comprising a flexible and substantially non-resilient contact-supporting ribbon movable to and held in contact-closing position by gravity and electromagnetic 60 means for deflecting said ribbon to break the circuit.

In testimony whereof I have hereunto subscribed my name this 29th day of June, 1900.

ALEXANDER JAY WURTS.
